LATCHING AND LOCKING MECHANISM FOR LOCKER DOORS AND THE LIKE

Jack E. Fohn, Aurora, Ill., assignor to Aurora Steel Products Company, Aurora, Ill., a corporation of Illinois

Application April 8, 1955, Serial No. 500,099

9 Claims. (Cl. 70—80)

The present invention relates to latching and locking mechanism for the doors of steel lockers, cabinets and the like.

One of the objects of the invention is to provide latching mechanism wherein the latches are released by an improved finger tip lifter that is recessed into the front surface of the door. This results in the door having a flush front, with no projecting handle or other fixed projections. Hence, there is a condensation of space in shipping—more doors can be nested together in a smaller space, with less likelihood of damage from breakage or scratching.

Another object of the invention is to provide an improved locking mechanism which can be readily converted from a padlock type of locking mechanism to a bolt type of locking mechanism in a more compact manner than heretofore, with fewer parts, and with less labor.

Another object is to provide improved escutcheon plate means so constructed as to receive the loop for the padlock type of lock, or to receive the bolt type of lock; and also so constructed as to define the front of the finger tip lifter recess to the door in which the finger tip lifter operates.

Another object is to provide improved escutcheon plate means comprising a front cover plate and locker number plate, according to which the number plate can be placed below the finger tip lifter recess when using one type of lock, and can be placed above the finger tip lifter recess when using the other type of lock. This combination of cover plate and number plate enables the same front cover plate and the same number plate to be used with either type of lock. It also avoids the necessity of a separate location for the number plate, and the necessity of separate means for fastening the number plate to the front of the locker. It also conceals the padlock loop from view when not needed, and eliminates any sign of provision for a bolt lock or flat key lock when it is not used. Still further, the improved front cover plate acts as a strike plate for the padlock when the latter is used, and prevents the padlock from striking and scraping against the painted surface of the door front.

Another object of the invention is to provide improved locking mechanism of the above general description which permits pre-locking, i. e., in which the lock mechanism may be locked while the door is in open position, and the door may thereafter be moved to a closed, locked position, without manually actuating the latching bar nor the finger tip lifter.

Another object of the invention is to provide an improved construction of latches, wherein the latches are constructed entirely of wire.

Another object of the invention is to provide a latching and locking mechanism of the above general description which will be very inexpensive to manufacture and assemble, so as to occupy a favorable position in a highly competitive market.

Other objects, features and advantages of the invention

2

tion will be apparent from the following detail description of two preferred embodiments of the invention. In the accompanying drawings illustrating such embodiments:

5 Figures 1 and 2 are perspective views of a locker embodying my invention;

Figure 3 is a front elevational view of the escutcheon plate portion of the latching and locking mechanism;

Figure 4 is a horizontal sectional view taken on the 10 plane of the line 4—4 of Figure 3;

Figure 5 is a vertical sectional view taken on the plane of the line 5—5 of Figure 3;

Figure 6 is an inner or back view of the latching and locking mechanism;

Figure 7 is a fragmentary sectional view taken on the plane of the line 7—7 of Figure 6;

Figure 8 is a fragmentary sectional view taken on the planes of the lines 8—8 of Figures 5 and 7;

Figure 9 is a sectional view taken on the planes of the lines 9—9 of Figures 5 and 7;

Figure 10 is an elevational view of the locker number plate;

Figure 11 is a view similar to Figure 3 but showing the locker number plate rearranged for a bolt type of lock;

Figure 12 is a vertical sectional view taken on the plane of the line 12—12 of Figure 11;

Figure 13 is an inner or back view showing the mounting of the bolt type of lock;

30 Figures 14 and 15 are front elevational views of a modified construction, illustrating the alternate arrangement for a padlock and for a bolt type of lock;

Figure 16 is an inner or back view showing the mounting of the bolt type of lock;

35 Figure 17 is a fragmentary rear view of the modified cover plate; and

Figure 18 is an elevational view of the modified locker number plate.

Referring first to Figures 1 and 2 which show the 40 general construction of a typical steel locker embodying my invention, this locker, designated 20, comprises the usual side walls 21, 21, back wall 22, and top and bottom walls 23, 23. The front opening 24 is defined by side angle bars 26 and 27, defining the jambs of the opening, and by upper and lower channel bars 18 and 19 which are welded to the jamb angle bars. The opening 24 is adapted to be closed by a door 25 which is connected by hinges 30 to the hinge side bar 27. The other side bar 26 functions as a locking side bar, and comprises a front marginal flange 28 and a rearwardly extending reenforcing flange 29. This latter latching bar 26 has secured thereto a plurality of vertically spaced keepers 40. As shown in Figures 4, 5 and 6, each keeper 40 is in the form of a stamping comprising an attaching flange 42 from which extends a rearwardly bent flange 43, a laterally bent flange 44, and a forwardly bent flange 45. The attaching flange 42 has riveted attachment to the inner side of the front marginal flange 28 of the locking angle bar 26. The forwardly extending flange 45 of each keeper 40 lies substantially in the plane of the door opening, and has a sloping nose portion 46 leading up to a vertical keeper notch 47. Cemented or vulcanized to the front face of the laterally bent flange 44 is a rubber cushioning pad 48 which is adapted to be engaged by the inner flange 52 at the latching edge of

45 the door.

Referring now to this latching edge of the door, it will be seen from Figure 4 that the sheet which constitutes the door is bent backwardly to form a marginal flange 51 and is then bent laterally to form an inner flange 52. These two flanges 51 and 52, together with the door panel, define a vertical channel-shaped trough

50

55

70

53 in which slides the vertically moving latching bar 55. This latching bar 55 is of channel shaped cross section, comprising the two spaced flanges 56, 56' and connecting web portion 57. The latching bar 55 is disposed in the channel shaped trough 53 with the web portion 57 in sliding engagement with the inner flange 52 of the door.

Punched out in this inner flange 52 of the door and in the web portion 57 of the latching bar 55 are matching slots 58 and 59 which are located at the heights of the keepers 40 so as to permit the keeper prongs 45 to enter the latch bar 55 on the door when the door is swung to closed position. There are preferably three vertically spaced keepers 40 and three sets of matching slots 58 and 59 for receiving these keepers, located at upper, intermediate and lower portions of the door respectively.

Referring to Figures 7-9, it will be seen that extending across the channel space between the two parallel flanges 56, 56' are pivot pins 64, and pivotally mounted on these pins 64 are latches 65. Each latch is made up of a section of round wire shaped in the form of two aligned coils 66, 66' having their adjacent ends joined together by a stirrup or U-shaped portion 68. The two aligned coils 66, 66' are mounted for free rotative movement upon the transverse pivot pin 64. The cross bar portion 70 of the stirrup shape 68 functions as the detent or latching element. The stirrup shape 68 and cross bar portion 70 are normally held in their substantially horizontal latching position by a resilient extension or tail 72 constituting one end of the section of wire. This tail end extends from the outer end of the coil 66' in a downward direction to play in the space between the panel of door 25 and the web portion 57 of the latching bar 55. The weight of the stirrup shape 68 and cross bar portion 70 normally tends to hold the latch with the tail extension 72 contacting the panel of the door 25, or hanging pendant in proximity thereto. The cross bar portion 70 is adapted to ride up the inclined nose 46 and to snap over the point of the vertical notch 57 of the associated keeper and rest at the bottom of the notch, with the tail 72 of the latch resting against web portion 57, but not under tension. These wire latches 65 are given a spring temper to make them resilient. The latching bar 55 does not have to move upward either during normal closing or prelocked closing, as the latches 65 can move into latching engagement with the keepers 40 independently of movement of the latching bar 55. The latches are only under tension when their extension tails 72 are pressing against the web portion 57 of the latching channel 55, and this only occurs during the last part of the upward ride of the portion 70 up the slope 46 of the keeper. The extension tails 72 serve to prevent the latches 65 from being gravitationally released by inversion, and thus prevent the locking mechanism from becoming released by a burglar or other unauthorized person inverting the entire locker 20 into an upside down position.

As shown in Figures 4 and 6, the latching bar 55 is adapted to be lifted to an unlatching position by a horizontally extending actuating rod 74 which extends laterally from an intermediate point of the latching bar. This actuating rod 74 is preferably mounted in aligned holes formed in the flanges 56, 56' of the latching bar 55, the rod or pin being headed over on the outer side of the flange 56'. Pivotally mounted on said actuating rod 74 is a finger tip lifter 75 (Figure 5) which lies directly behind a finger tip recess or opening 76 of rectangular outline, punched out of the door. This finger tip lifter comprises a plate 77 having two pivot ears 78 bent rearwardly from the sides of the plate, these ears being provided with pivot apertures 79 which have pivotal mounting upon the actuating rod 74. Projecting inwardly from the lower edge of the plate is a finger tip flange 80 of V-shaped cross section which affords an engaging surface adapted to be engaged by the finger tips in the act of releasing the latching mechanism. In this

latch releasing operation the tips of the fingers are inserted into the recess 76 and engaged with the lifting surface 80, through which an upwardly lifting pressure is transmitted to the actuating rod 74. This upward lifting force slides the latching bar 55 upwardly and carries the cross bar portions 70 of the latches out of the notches 47 in the keepers 40, thereby freeing the door for swinging movement into opening position.

Formed in the panel of the door (Figures 3 and 5) are upper and lower or first and second openings 81 and 82. The upper or first opening 81 is above the finger tip recess 76 for receiving the padlock loop, and the lower or second opening 82 is below the finger tip recess 76 for receiving the lock barrel of the bolt type of lock. Referring to Figure 5, it will be seen that anchored to the upper portion of lifter plate 77 and projecting forwardly therefrom is a padlock receiving loop 83. This loop is adapted to be projected outwardly through the aforesaid first opening 81, which may be in the form of a slot punched out in the door at a point above the rectangular finger tip opening 76. The weight of the plate 77 and of the padlock receiving loop 83 is forward of the pivotal axis of the plate on the actuating rod 74, with the result that the padlock receiving loop 83 is constantly biased into the direction to swing outwardly through the slot 81. However, the loop 83 can only be projected outwardly through the slot 81 when the latching bar 55 is in its lower latching position. When the loop 83 is thus projected outwardly through the slot 81, upward movement of the finger tip lifting plate 77 and of the actuating rod 74 is precluded, with the result that the latching bar 55 is locked in its lower door-locking position. It will be observed from Figure 5 that the finger tip engaging surface 80 is located below and slightly in front of the axis of pivotal mounting of the lifter 75 on actuating rod 74. By virtue of this location, upward finger pressure on the engaging surface 80 tends to rock the plate 77 in a rearward direction to retract the padlock receiving loop 83 out of the slot 81. In addition to the upward lifting force exerted through the finger tips, a forward pulling force is also applied for the purpose of opening the door, and this forward pulling force acting through the lifting surface 80 establishes a further force for pivoting the padlock receiving loop 83 rearwardly into releasing position, clear of the slot 81 in the door, in which released position the latching bar 55 moves upwardly under the lifting force for releasing the three latches 65 from their keepers 40.

Referring to Figures 4 to 6, a housing 85 is mounted to enclose the back side of the finger tip recess 76 and of the finger tip lifter 75. This housing comprises a plate portion 86 spaced rearwardly from the inner side of the door to provide a finger tip space 87 therebetween. The housing is closed on three sides by a forwardly extending side flange 88 and by forwardly extending end flanges 89 and 90, and is open on the fourth side adjacent to the latching bar 55. The actuating rod 74 enters the housing 85 through this open side and extends through to the opposite side where it has guided engagement in a slot 91 punched out in the side flange 88. The end flanges 89 and 90 of the housing have apertured attaching flanges 94 which are secured to the inner side of the door by first and second bolts 95 and 95' which pass through holes 96 in the door and receive nuts 97 on their inner ends. These bolts have smooth outer heads so that they can not be surreptitiously removed from the front of the door. The inward swinging motion of the lifter plate 77, in response to lifting and opening pressure exerted on the lifting surface 80, is limited by the back edge of the plate striking the inner surface of the housing 85, in which position the padlock receiving loop 83 is clear of the slot 81, but wherein the plate 77 and padlock receiving loop 83 are still gravitationally biased in a forward direction, so that when lifting pressure is removed from the lifting surface 80

the padlock receiving loop 83 immediately tends to fall back out through the slot 81.

Adapted for mounting on the inner side of the door immediately below the housing 85 is a bolt type or flat key type of lock 98, shown in Figures 11 to 13. This lock comprises a housing 99 having apertured ears 101 which are secured to the inner side of the door by the aforementioned second bolt 95', and by a third bolt 95" also passing through a hole 96" in the door. This lock has a key receiving barrel portion 102 which projects forwardly through the aforesaid second opening 82 which is provided in the door at a point below the finger tip recess 76. Adapted for lateral projection from the lock housing 99 is a locking bolt 106. When this bolt is projected laterally from the lock housing, it is adapted to enter a slot 108 which is punched out in the flange 56 of the latching bar 55. When thus projected into the slot 108, the latching bar 55 is positively locked in its lower locking position, with the latches 65 held in the keeper notches 47, thereby positively locking the door 25 in closed position.

Mounted on the front side of the door is escutcheon plate means 109 which is adapted to optionally cover either the first opening 81 or the second opening 82, depending upon whether the bolt type of lock or the padlock is intended to be used. This escutcheon plate means comprises a combination cover plate 110 and locker number plate 111, the latter being shown in Figure 10. The cover plate 110 comprises a large central opening 112 of rectangular configuration to match with the rectangular finger tip opening 76 cut in the door. The cover plate 110 also comprises an upper vertical slot 113 and a lower circular opening 114. The upper vertical slot 113 aligns with the upper opening 81 in the door to receive the padlock receiving loop 83, and the lower circular opening 114 aligns with the lower opening 82 in the door to receive the barrel portion 102 of the bolt type of lock 98. In addition, this cover plate 110 has apertures 115, 115' and 115" for receiving the top, intermediate and bottom fastening bolts 95, 95' and 95".

The cover plate 110 is embossed with forwardly projecting ribs 116, 116 along its vertical side edges, and also with upper and lower transverse ribs 117 and 118 joining the side ribs 116, 116. The upper transverse rib 117 and the two side ribs 116, 116 form three sides of an upper flat pocket area 121. The rectangular slot 113 for projecting the padlock receiving loop 81 opens into this upper pocket area 121. The lower transverse rib 118 joins with the two side ribs 116, 116 in forming the three sides of a lower flat pocket area 123. The circular aperture 114 for receiving the lock barrel 102 opens into this lower pocket area 123. The top edge of the upper transverse rib 117 is formed with a downwardly opening slot 122 (Figure 5) and the top edge of the lower transverse rib 118 is formed with a similar downwardly opening slot 124. These two slots are adapted to receive selectively the tab 127 on the lower portion of the locker numbering plate 111, which I shall now describe.

This locker number plate 111, shown in Figure 10, carries the locker number *n*, and may also be provided with indicia designating the name of the manufacturer, or the name of the school or establishment in which the lockers are installed. The upper edge of the number plate has an aperture 126 for receiving either the upper or intermediate bolt 95 or 95', and the lower edge has an extending tab 127 adapted to be inserted in either of the slots 122 or 124. When the locker door is intended to be locked with the bolt type of lock 98, the locker number plate 111 is inserted in the upper pocket area 121, with the upper bolt 95 passing through the number plate aperture 126, and with the number plate tab 127 engaging in the upper slot 122. In this position of the number plate 111, it effectively blocks off the

slot 113 in the cover plate 110, so that the padlock receiving loop 83 is held in its retracted position in the housing 85, in which position the finger tip lifter 75 is still free to move the latching bar 55 upwardly for releasing the wire latches or keepers 65. Thus, in this position of the number plate 111, all locking of the locker door is effected by the flat key or bolt type of lock 98.

On the other hand, when the locker door is intended to be locked with a padlock 130, the locker number plate 111 is removed from the upper pocket area 121 and is inserted into the lower pocket area 123, with the intermediate bolt 95' passing through the aperture 126, and with the tab 127 engaging in the lower slot 124. In this position of the number plate, the upper slot 113 in the cover plate 110 is opened so that the padlock receiving loop 83 can be projected out through this slot for receiving the padlock type of lock 130. In this latter situation, the bolt type of lock 98 is preferably removed, so that there will be no locking barrel 102 projecting through the circular opening 114 in the cover plate 110, and the number plate 111 can be inserted in the lower position on cover plate 110 to cover the circular opening 114. Alternatively, a construction of lock 98 may be employed in which the lock barrel 102 has its outer end terminating substantially flush with the outer surface of the cover plate 110.

Referring now to the modified construction illustrated in Figures 14 to 18 inclusive, in this modified construction the escutcheon plate means 109a is arranged to be reversed end for end in converting the locking mechanism from the padlock type of lock to the bolt type of lock, and vice versa. This modified form of escutcheon plate means 109a comprises a combination cover plate 110a and locker number plate 111a. The cover plate 110a comprises a large rectangular finger tip opening 112a in the center, a smaller rectangular opening 113a at one end, and a circular opening 114a at the other end. The cover plate 110a may be secured by bolts 95, 95' as previously described, but, as illustrative of a modified arrangement I have shown this cover plate 110a as being provided with rearwardly projecting bolts 139, 139 for passing through upper and lower bolt holes 96, 96" in the door, these bolts receiving nuts 142 on their inner ends.

The locker number plate 111a is a plain rectangular plate carrying the locker number *n*. This number plate 111a is adapted to be placed on the back side of that end of the cover plate 110a which is provided with the rectangular opening 113a, the locker number *n* being exposed through this rectangular opening 113a. A pocket 144 is recessed or indented in the back side of the cover plate 110a for receiving the number plate 111a.

When the locking mechanism is intended to be locked with a padlock, the cover plate 110a is so placed on the door that the end which carries the circular hole 114a is uppermost, as shown in Figure 14. The padlock loop 83 is then free to be projected out through this circular hole 114a. The number plate 111a is placed in back of the small rectangular opening 113a, with the number indicia *n* in its proper erect position. The cover plate 110a is held fast in this position by drawing the nuts 142 up tight on the bolts 139.

When the locking mechanism is intended to be locked with a bolt type of flat key lock 98a, the cover plate 110a is reversed end-for-end, so as to dispose the circular hole 114a at the lower end of the cover plate 110a in position to receive the cylindrical barrel 102a of the bolt type of lock. For this reversed position of the cover plate 110a, the number plate 111a must be removed and reversed top and bottom so that the number indicia *n* will be in its proper erect position. In its position at the upper end of the cover plate 110a, the number plate 111a closes off the slot 81 in the door so that the padlock receiving loop 83 is held in its retracted position in housing 85a. In

this embodiment, the bolt type of lock 98a has only one attaching ear 101a. The lower bolt 139 passes through the aperture in this ear and fixedly secures the bolt type of lock and the lower end of the cover plate 110a to the door panel. In this embodiment, the housing 85a is held in place by the upper bolt 139 passing through an upper apertured attaching flange 94a projecting from the upper edge of the housing. The lower edge of the housing has a lip 94' which is clamped under the bolt type of lock 98a when this latter type of lock is used.

While I have illustrated and described what I regard to be the preferred embodiments of my invention, nevertheless it will be understood that such are merely exemplary and that numerous modifications and rearrangements may be made therein without departing from the essence of the invention.

I claim:

1. In a locker having an opening, a door closing said opening, latch means carried by said door for latching it closed, a latch bar carried by said door for releasing said latch means, handle means for actuating said latch bar, a padlock receiving loop adapted to lock said latch bar against latch releasing movement, a bolt type of lock adapted to lock said latch bar against latch releasing movement, said bolt type of lock having a key barrel, a cover plate mounted on said door in association with said handle means, said cover plate having two openings therein for receiving said padlock loop and for receiving said key barrel, and a locker number plate adapted for mounting on said cover plate in position to close one of said openings.

2. In a locker having an opening, a door closing said opening, latch means carried by said door for latching it closed, a latch bar carried by said door for releasing said latch means, a recess in said door, a finger tip lifter in said recess operatively connected with said latch bar, a cover plate, a finger tip opening in said cover plate matching with said recess in the door, two holes in said cover plate spaced vertically from said finger tip opening, a padlock receiving loop connected with said finger tip lifter and adapted to be projected outwardly through one of said holes for locking said lifter against latch releasing movement, a bolt type of lock adapted for locking said latch bar against latch releasing movement, said bolt type lock adapted to have key receiving access through the other of said holes, and a locker number plate adapted to be mounted on said cover plate covering the appropriate hole to prevent the outward projection of said padlock receiving loop when the bolt type of lock is employed for locking.

3. In a locker having an opening, a door closing said opening, a latch means carried by said door for latching it closed, a latch bar carried by said door for releasing said latch means, a finger tip recess in said door, a finger tip lifter in said recess operatively connected with said latch bar, a first hole in said door spaced vertically in one direction from said finger tip recess, a padlock receiving loop connected with said finger tip lifter and adapted to be projected outwardly through said first hole into padlock receiving position for locking said lifter against latch releasing movement, a second hole in said door spaced vertically in the other direction from said finger tip recess, a bolt type of lock adapted for locking said latch bar against latch releasing movement, said bolt type of lock having a key receiving barrel adapted to extend through said second hole, a cover plate, a finger tip opening therein adapted to register with said finger tip recess in said door, holes in said cover plate adapted to register with said first and second holes in said door, and a locker number plate carried by said cover plate and adapted to close off said first hole in the door when the bolt type of lock is employed, and adapted to close off said second hole in the door when the padlock is employed.

4. In a locker having an opening, a door closing said

opening, latch means carried by said door for latching it closed, a latch bar carried by said door for releasing said latch means, a finger tip recess in said door, a finger tip lifter in said recess operatively connected with said latch bar, a first hole in said door above said finger tip recess, a padlock receiving loop connected with said finger tip lifter and adapted to be projected outwardly through said first hole into padlock receiving position for locking said lifter against latch releasing movement, a second hole in said door below said finger tip recess, a bolt type of lock adapted for locking said latch bar against latch releasing movement, said bolt type of lock having a key receiving barrel adapted to extend through said second hole, a cover plate, a finger tip opening therein adapted to register with said finger tip recess in said door, an upper aperture in said cover plate adapted to register with said first hole in the door, a lower aperture in said cover plate adapted to register with said second hole in the door, and a locker number plate carried by said cover plate and adapted to close off said upper aperture when the bolt type of lock is employed, and adapted to close off said lower aperture when the padlock is employed.

5. In a locker having an opening, a door closing said opening, latch means carried by said door for latching it closed, a latch bar carried by said door for releasing said latch means, a finger tip recess in said door, a finger tip lifter in said recess operatively connected with said latch bar, a first hole in said door above said finger tip recess, a padlock receiving loop connected with said finger tip lifter and adapted to be projected outwardly through said first hole into padlock receiving position for locking said lifter against latch releasing movement, a second hole in said door below said finger tip recess, a bolt type of lock adapted for locking said latch bar against latch releasing movement, said bolt type of lock having a key receiving barrel adapted to extend through said second hole, a cover plate, a finger tip opening therein adapted to register with said finger tip recess in said door, an upper aperture in said cover plate adapted to register with said first hole in the door, an upper slot in said cover plate associated with said upper aperture, a lower aperture in said cover plate adapted to register with said second hole in the door, a lower slot in said cover plate associated with said lower aperture, and a locker number plate adapted to be carried by said cover plate in an upper position closing off said upper aperture, or in a lower position closing off said lower aperture, said locker number plate having a projecting lug receivable in said upper slot or in said lower slot when in either of said positions.

6. In a locker having an opening, a door closing said opening, latch means carried by said door for latching it closed, a latch bar carried by said door for releasing said latch means, a finger tip recess in said door, a finger tip lifter in said recess operatively connected with said latch bar, a first hole in said door above said finger tip recess, a padlock receiving loop connected with said finger tip lifter and adapted to be projected outwardly through said first hole into padlock receiving position for locking said lifter against latch releasing movement, a second hole in said door below said finger tip recess, a bolt type of lock adapted for locking said latch bar against latch releasing movement, said bolt type of lock having a key receiving barrel adapted to extend through said second hole, a cover plate, a finger tip opening therein adapted to register with said finger tip recess in said door, apertures in said cover plate adapted to register with said first and second holes in said door, and a locker number plate carried by said cover plate in registration with one of said apertures, said cover plate being invertible end-for-end for placing said locker number plate over said first hole when the bolt type of lock is employed, and for placing said locker number plate over said second hole when said padlock is employed.

7. In a locker having an opening, a door closing said opening, latch means carried by said door for latching it closed, a latch bar for controlling said latch means, a finger tip recess in said door, a pivot carried by said door in association with said recess, a finger tip lifter pivotally mounted in said recess on said pivot and operatively connected with said latch bar for lifting the latter, said lifter comprising an extending plate portion, a padlock receiving loop projecting from said plate portion, and an aperture in the door through which said loop is normally projected, said lifter having pivotal movement around said pivot under lifting pressure in a direction for retracting said loop out of said aperture.

8. In a locker having an opening, a door closing said opening, latch means carried by said door for latching it closed, a latch bar carried by said door for releasing said latch means, a padlock receiving loop adapted to lock said latch bar against latch releasing movement, handle means pivotally and slidably mounted on said door and operatively connected with said padlock receiving loop, said handle means being operative by pivotal movement thereof to first exert a force on said loop in a retractive direction and being then operative by sliding movement thereof to impart sliding movement to said latch bar, a bolt type of lock adapted to lock said latch bar against latch releasing movement, said bolt type of lock having a key barrel, a cover plate mounted on said door in association with said handle means, said cover plate having two openings therein, one for receiving said padlock loop and one for receiving said key barrel, and a plate adapted for

mounting on said cover plate in position to close one of said openings.

9. In a locker having an opening, a door closing said opening, latch means carried by said door for latching it closed, a latch bar carried by said door for releasing said latch means, recessed handle means pivotally mounted on said latch bar for actuating said latch bar, a padlock receiving loop adapted to lock said latch bar against latch releasing movement, a bolt type of lock adapted to lock said latch bar against latch releasing movement, said bolt type of lock having a key barrel, a cover plate mounted on said door in association with said handle means, said cover plate having two openings therein, one for receiving said padlock loop and one for receiving said key barrel, and a closure plate adapted for interchangeable mounting on said cover plate in position to close either one of said openings.
